UNITED STATES PATENT OFFICE

ERVIN W. McCULLOUGH, OF INDIANAPOLIS, INDIANA

RENDERING TANK DOOR

Application filed November 8, 1926. Serial No. 147,096.

This invention relates to a tank.

The chief object of this invention is to provide a tank with suitable means for drainably sustaining a load of a peculiar character, thereby permitting the saturation and drainage thereof through said load sustaining means without substantial interference, the clogging of the load sustaining means, or the escape of any appreciable amount of the solids contents.

The chief feature of the invention consists in the formation of a chamber-forming opening in a tank of the character indicated and associating therewith a perforated load-supporting plate and an opening closure, said closure and plate being in spaced relation, interposed between which is a filtering or screening medium of suitable character, such as softened excelsior or other similar suitable fibrous material, or its equivalent.

The full nature of the invention will be understood from the accompanying drawings and the following description and claims:

In the drawings Fig. 1 is an elevational view of a tank of the character indicated, parts being shown in section to illustrate other parts in detail. Fig. 2 is a transverse sectional view of the invention taken in the plane of 2-2 in Fig. 1 and in the direction of the arrows. Fig. 3 is a perspective view of one form of the load sustaining drainer. Fig. 4 is a front elevational view thereof. Fig. 5 is a central sectional view of a modified form of the invention.

This invention is an improvement upon, and an extension of the invention disclosed originally in application Serial No. 653,403, filed July 23, 1928, entitled Garbage reducer, and is of such a character that it is more satisfactory for operation in a garbage tankage extraction process such as disclosed in the pending application Serial No. 63,163, filed October 17, 1925, and entitled Garbage

tankage extraction than the invention generically claimed and described in the aforesaid garbage reducer application. The present application is a continuation in part of copending application Serial No. 63,163.

In the drawings 10 indicates a suitable frame-work which rigidly supports a vertically disposed cylindrical tank having a lower portion 11 and the upper portion 12. Lower portion 11 is provided with an inner shell 13, whereby a heating jacket 14 is provided therebetween which encloses substantially the lower half of the tank. The two shells are provided with lower end closures 16 and 17 which form a heating space 18 therebetween. A suitable spacing means 19 maintains the two shells in spaced relation in addition to other supporting means that may be provided. Said spacing means 19 surrounds a rotatable shaft 20 extending from without the tank to within the same with its upper end terminating in an agitator construction including hub 21, curved arms 22 and agitator blades 23, said blades being arranged parallel to each other and at different distances respectively from shaft 20 so that they will track in individual paths when the shaft 20 is revolved. Shaft 20 is rotated by an annular rack 24 which meshes with a pinion 25 driven by a speed reduction mechanism 26, in turn driven by an electric motor or other suitable power means 27.

The upper portion of the tank includes a dome 28 having a neck 29 closed by a cap 30. Communicating with the neck is a passage 31 connected by a T to the valve-controlled lines 33 and 34. One of these valve controlled lines is adapted to supply pressure in the form of compressed air, steam or the like, to the tank for pressing, and the other is adapted to exhaust or apply a vacuum to the tank, the valves being differentially operable. The upper portion of the tank also is provided with a gage glass construction 35,

particularly for indicating the height of the extracting liquid in the tank supplied near the bottom thereof.

As shown clearly in Fig. 2, the jacket 14 has leading to it a plurality of supply lines 36 and a discharge line 37 including the trap 38, see Fig. 1, drains the same. The lower portion of the inner shell 13 is provided with supply lines 39 and steam or compressed air 20 may be supplied to the tank contents through these pipes.

The tank near the bottom thereof is provided with an opening-defining and tubular frame 41 which includes a passage 42 in communication with a line 43 controlled by the valve 44. The tubular frame exterior opening is closed by a suitable door or closure plate 45 having multiple hinge construction for substantially forward movement of the door 15 for a considerable distance, such movement being provided for clearance purposes. Said hinge includes ears 146, pivots 46 and 246 and links 346. Readily operable locking means 47 secure the closure or door 45 in 20 closed relation with the frame 41. Attached to the door 45 and extending inwardly into the space formed by the frame are a plurality of abutments 48 to which is suitably secured load sustaining perforated plate means 49 25 in the form of a boxing including but four sides, the top and the side adjacent door 45 being open. The perforations of the boxing comprise a small number of large openings and a relatively large number of small openings.

Included within the boxing is a filtering medium. Such a suitable medium has been found to be boiled or softened excelsior. Other softened fibrous material or softened 40 shredded material will be satisfactory for the purpose. Specially arranged granular material may be employed. The device herein disclosed is particularly adaptable to the admission through line 43 of a solvent which 45 under pressure is forced into the tankage and permeates the same, following which it is withdrawn through the same line from the tankage with the solvent extracted constituent included therein. The character of the 50 permeable material is such that the majority of it is of considerable fineness and in the withdrawal of the solvent a considerable portion of the finer materials would be carried with it. The filtering or straining mechanism 55 herein disclosed prevents such action, but does not introduce any considerable resistance to the free entrance and egress of the solvent to and from the tankage.

In Fig. 3 the open face boxing comprises 60 the front plate 49 which is curved to conform substantially to the cylindrical outline of the tank and complement the same. The two substantially parallel sides 50 and 51 are connected by a bottom 52. The other or back 55 face is formed by the door 45 when the box-

ing is mounted upon said door as shown in Fig. 2. There is thus formed a filtering material containing boxing carried by the door and receivable in the chamber-forming opening in the frame 41. Suitable filtering material as previously described, consists of softened or boiled excelsior which is positioned in the boxing.

In Fig. 5 a modified form of the invention is illustrated in central section. A cover plate 53 is provided which is pivotally mounted in ears 54 formed in the boxing at opposite sides and bears upon the bracket or stop lug 55. Thus, the filtering material is completely enclosed in this form of the invention.

It will be readily appreciated that when the locking means 47 is released, said door can first be retracted axially of the opening to remove the boxing and thereafter swung laterally to completely expose the opening without interference from the boxing or the door closure since in this form of the invention the boxing and door are unitary and simultaneously movable. The tankage thereafter may be removed from the tank by manual manipulation or mechanically by the operation of the agitator. The device herein described is peculiarly adaptable to garbage tankage extraction such as set forth in 95 the copending application Serial No. 63,163, filed October 17, 1925, and entitled Garbage tankage extraction. The form of filter arrangement including the load sustaining and separating plate may, if desired, be employed 100 in the standard rendering tank for the purpose set forth in the application Serial No. 698,106 and thus is an adequate substitution for the combination rendering tank disclosed in the application entitled Garbage reducer, 105 Serial No. 653,403, filed July 23, 1923.

The invention claimed is:

1. In a garbage extraction tank having a curved side wall and a discharge opening therein and a frame work therefor, a closure 110 for said opening movably mounted on said frame work, a one-piece apertured plate consisting of three sides and a bottom portion being mounted on said closure and so spaced therefrom as to be flush with the side walls of 115 said tank, the middle one of the side walls of said plate being shaped to conform to the interior surface of the tank side wall, the said plate, closure and framework together forming a chamber adapted to contain a filtering 120 medium.

2. In a garbage extraction tank having a curved side wall with a discharge opening therein, a framework surrounding the opening and constituting a passageway communicating with the tank through the opening, a closure for said passageway movably mounted for closing the framework defined opening, a perforated plate shaped to conform to and forming a part of the interior of the tank side 130

wall and in spaced relation to the closure, walls interposed between the closure and the plate forming a filtering chamber within the passageway, a filtering medium in said chamber and movable with the closure, and conduit means for liquid flow communicating with the passageway and with the tank interior through the filtering chamber.

In witness whereof, I have hereunto affixed
19 my signature.

ERVIN W. McCULLOUGH.
